United States Patent Office

Des. 229,740
Patented Jan. 1, 1974

229,740

LITTER BIN OR SIMILAR ARTICLE

Harry Zelenko, 240 E. 61st St.,
New York, N.Y. 10021

Continuation-in-part of design application Ser. No. 141,096, May 6, 1971. This application Jan. 9, 1973, Ser. No. 322,161

Term of patent 14 years

Int. Cl. D20—99

U.S. Cl. D7—194

FIG. 1

FIG. 3

FIG. 4

FIG. 2

FIG. 5

FIG. 1 is a perspective view of a litter bin, or similar article, showing my new design;

FIG. 2 is a front elevational view thereof;

FIG. 3 is a side elevational view thereof;

FIG. 4 is a top plan view thereof; and

FIG. 5 is a rear elevational view thereof.

This application is a continuation-in-part of my co-pending design patent application Ser. No. 141,096 filed May 6, 1971.

I claim:

The ornamental design for a litter bin or similar article, substantially as shown and described.
